MEANS FOR PREVENTING TAKING OF FRAUDULENT IMPRESSIONS FROM POSTAGE
METER MACHINES

Application filed November 6, 1930. Serial No. 493,896.

The particular object of this invention is to provide novel means for preventing fraudulent impressions being taken from flat printing dies by curved or rocking impression means; or from curved printing dies such as are used on postage meters and the like as shown for example in the so-called "Model H" machine as described in our companion application (case 7614) filed March 8, 1929, 10 Serial No. 345,515. In such "Model H" machine a curved segmental printing die is mounted in the periphery of a rotatable drum or support and comes into operative relation once for and during each rotation of the 15 drum with the paper or envelope to be imprinted; a cylindric roller usually cooperating with the die to take an impression. If the drum was stopped when the die was exposed fraudulent imprints might be taken 20 therefrom by simulating the action of the pressure roller and the present invention provides means whereby the taking of fraudulent impressions are prevented.

To prevent securing of more than one impression from the die without a complete revolution of the drum, which is necessary to obtain accurate registration, the die was housed in the drum and drum casing so that only a very small portion of the periphery 25 of the die was exposed at the printing point at one time, so that it would be necessary to complete a revolution of the drum to secure a complete impression (the rotation of the drum being non-reversible). This however 30 is objectionable especially when rather long dies are used (as in the Model "H" machine) as the housing has to be so close to the printing face of the envelope going through the 35 machine that it drags and retards the progress of the envelope and presents an edge or lip on which the envelope is likely to catch.

Our invention provides what we term a "protector" for the die whereby an impression can only be obtained by causing the 40 drum to rotate and move the die relatively to impression means, so that the impression will be taken successively from the front end of the die back to the rear end thereof, and an impression cannot be taken from all points 45 of the die simultaneously. This protector 50

can be mounted in the drum or die support and move with the die, and will not retard the passage of an envelope if it happens to contact therewith; and does not produce any obstruction upon which the envelope could 55 catch.

We use the term "envelope" in a generic sense to designate the matter to be imprinted, and to include any matter which may be imprinted by the die. The term "die" is also 60 intended to include any suitable kind or make of printing surface.

In the accompanying drawings we have illustrated some practical embodiments of the invention which we will hereinafter describe 65 to enable others skilled in the art to adapt and use the same, the several modifications referred to merely showing the possibility of embodying the invention in various mechanical forms, and not as limiting the invention to any specific construction shown. In the claims we have set forth the essentials of the invention, and also certain novel features and combinations of parts for which 70 protection is desired. 75

In said drawings:

Fig. 1 is a front elevation partly in section of part of the printing drum and die of a "Model H" postage meter equipped with our novel die protector and one means for 80 operating same. Fig. 2 is a side view of Fig. 1. Fig. 3 is a plan view of the die and protector assembled. Fig. 4 is a view similar to Fig. 1 showing another means for operating the protector. Fig. 5 is a side view 85 of Fig. 4, partly in section. Fig. 6 is a detail view of the drum and protector device shown in Fig. 4 showing the parts in another position. Figs. 7 and 8 are detail plan and side views of the die. Figs. 9 and 10 are detail plan and side views of the protector 90 detached and Figs. 11 and 12 are detail plan and side views of the protector applied to the die. 95

In the "Model H" machine, as described in our aforesaid application, the value printing die 2 is mounted at or in an opening in the periphery of a rotatable cylinder or drum 1, and the printing is performed by rotating the drum on its axis; and once during 100

each revolution of the drum the die cooperates with an impression roller 101 to make an imprint on an envelope passed between them.

5 The value printing die 2 has an approximately rectangular body 2a and a curved printing surface 2b (see Figs. 7 and 8). The die protector is an approximately rectangular frame having side members 3, an end member 3b and adjacent the opposite end a cross tie rod 3d (see Figs. 9 and 10). The protector practically encloses the body of the die 2 (see Figs. 11 and 12) and its sides are pivoted at 3a to the body of the die so the 10 protector can rock upon such pivots. The ends 3b and 3c are adapted to project beyond the printing surface of the die. Either end member 3b or 3c can be caused to project beyond the surface of the die. In the 15 construction shown by rocking the protector either the end 3b (or 3c) may be pressed inward flush with the surface of the side and the other end simultaneously projected beyond the surface of the die (and vice versa) 20 and when so positioned the surface of the inwardly pressed member conforms to the curvature of the die. The curved surfaces of the ends 3b, 3c may if desired virtually form parts of the die and are preferably engraved with some part of the indicia, it is 25 desired to print, thus making them serve as parts of the die.

Owing to the pivotal mounting of the protector one or the other of the ends 3b, 3c 30 must of necessity project beyond the printing surface, when the other is retracted. This will prevent the simultaneous taking of an impression from the full surface of the die. In the printing operation however 35 the pressure is progressively applied to the die by rolling contact, the entire surface never being under pressure at one and the same time. Therefore when the drum is revolved (in the direction of the arrow Figs. 40 1, 4, 6), the impression roller 101 first contacts the projecting end 3b and pushes it inward (until flush with the die surface) thereby rocking the protector and simultaneously projecting the other end 3c beyond 45 the die surface, the end 3c not then having arrived at the printing point. When the 50 projecting end 3c approaches the printing point it will be engaged by the impression roller 101 and pushed in flush with the surface of the die and take its part in making the impression, while simultaneously the end 3b, which has then passed the printing point 55 will be projected; but this can cause no damage as the impression from the adjacent part of the die has already been made. The same negative results will occur when the die is passing over the inking roller 4, for its supply of ink.

60 As it is necessary to rock the protector 3

by alternately retracting and projecting the ends 3b and 3c for every imprint made; and therefore any means or device that prevents such movements will also prevent the making of an imprint. Various means could be employed to hold the end 3c projected so that a fraudulent impression could not be made, but it is only when the die is exposed so that it could be tampered with that the 70 protector has to function.

75 In the preferred construction shown in Figs. 1 and 2 one end of the rod 3d is extended through a slot in the back wall 1a of the drum, and carries a roller 3e which engages a race cam slot 10 in the wall 11 of the 80 meter housing in rear of the drum. The cam slot 10 extends around the axis of rotation of the drum, and roller 3e engaging said slot keeps the protector under positive control at all times. The groove 10 has properly 85 shaped deflecting portions at the points where it is necessary to rock the protector to alternately retract and project the members 3b, 3c when passing the impression point or roller, and also when passing the inking 90 roller 4. As the drum is prevented by suitable means (not shown) from being turned in a reverse direction the positive control of the protector is effectual.

95 Another means for operating the protector is shown in Figs. 4-6. As shown in the printing drum 1 is a dash pot 5 having a piston 5a and rod 5b projected by a spring 5s. The outer part of rod 5b is provided 100 with ratchet teeth 5c, and said rod has a stud 5d which projects through a slot in the rear wall 1a of the drum and carries a roller 5e adapted to engage a projecting convolute cam 7 on the inner face of the rear wall 11 of the meter housing 11a or drum casing in 105 rear of the drum.

A pawl 6 is pivoted at 6a in the drum and is adapted to engage the ratchet teeth 5c. Said pawl has an arm 6b carrying a stud 6d 110 projecting through a slot in the back wall 1a of drum 1 and having a roller 6e on its rear end adapted to engage a projecting convolute cam 8 on wall 11. A spring 6s normally urges the pawl 6 into engagement with the 115 ratchet teeth 5c.

The rod 3d of the protector lies directly in the path of travel of the piston rod 5b, and if the piston rod 5b is projected out of the dash pot 5 it will engage rod 3d and be held in this position by the pawl 6 and prevent the projector end 3c of the projector being pushed back into the drum. If the piston rod is projected it will be retracted after the die has passed the printing position during the revolution of the drum as the roller 6e will contact with cam 8 and be thereby caused to move inward toward the center of the drum and disengage pawl 6 from the ratchet teeth 5c. Then the roller 5e will contact with cam 7 and be thereby 120 125 130

5 moved inward and retract the piston rod 5b. Both the piston rod and pawl will retain their restored inactive positions until just before the forward end of the die again reaches the printing point. Then both rollers 5e and 6e will disengage their respective cams, and the piston rod is projected toward the rod 3d on the protector. The speed of 10 outward movement of the piston rod is controlled by the dash pot, which is so adjusted that the interval of time required by the dash pot for moving the piston rod to its effective position will be sufficient to permit completing an impression from the die in 15 the normal operation of the machine; instead of the dash pot other suitable means may be used to delay the action of the lock.

We do not consider this invention limited to any of the specific mechanisms disclosed 20 above.

Also it is not essential that the ends of the protector 3b and 3c be engraved to make them part of the indicia, as they may be made to act as plain bars projecting above the 25 printing surface from the sides of the die and depressed below the printing surface when passing the printing point as illustrated in Fig. 12.

We consider the structure shown in Fig. 1 30 is simpler and just as effective as the dash pot structure shown in Figs. 4 and 6. Obviously the protector might be used with a flat die, against which a full impression is taken in sequence by a rocking platen or a 35 reciprocating roller. The essential feature of the invention is that a protecting device 40 preferably adjacent the front and rear ends of the die would be operated substantially as described for each proper single impression operation and prevent taking a second or 45 fraudulent impression from the die when the latter is exposed adjacent the printing point.

We claim:

1. In combination with a rotatable printing die; spaced devices adapted to be alternately projected beyond the printing surface of the die to permit taking a progressive impression from the surface of the die, but preventing the taking of a simultaneous impression from all portions of such surface; and means for retracting one device and simultaneously projecting the other while the die is exposed for printing.

2. In combination with a rotary printing 55 die, devices adjacent opposite ends of the die and adapted to be alternately projected beyond the printing surface of the die said devices permitting the taking of a progressive impression from the surface of the die, and preventing the taking of a simultaneous 60 impression from all parts of such surface; and means for retracting one device and simultaneously projecting the other while the die is exposed for printing.

3. In combination with a printing die; a

rocking protector having spaced members adapted to project beyond the impression surface of the die and permit taking a progressive impression from the surface of the die but prevent obtaining a simultaneous 70 impression from all parts of such surface.

4. In combination with a printing die; a rocking protector having spaced projections on its ends adapted to project alternately beyond the printing surface of the die and permit taking a progressive impression from the surface of the die but to prevent taking a simultaneous impression from all parts of such surface, and means for operating said 75 protector.

5. In combination a rotary drum, a printing die mounted in the drum, protector means in the drum adapted to alternately project beyond the printing surface of the die and permit taking a progressive impression from the surface of the die but prevent taking a simultaneous impression from all parts of such surface.

6. In combination a rotatable drum, a printing die therein, and protector devices in the drum adjacent opposite ends of the die adapted to alternately project beyond the printing surface of the die to prevent taking a simultaneous impression from all parts of the printing surface; and means for retracting and projecting said devices during the 90 rotation of the drum.

7. In combination a rotary drum, a printing die therein, protector devices in the drum adjacent opposite ends of the die adapted to project beyond the printing surface of the die to prevent taking a simultaneous impression from all parts of the printing surface, and means for retracting one device and simultaneously projecting the other during the 100 rotation of the drum and the taking of an impression from the die.

8. In combination with a printing die; protector means adapted to project beyond the impression surface of the die to prevent the taking of a simultaneous imprint from all portions of the printing surface of the die, and means for operating the protector.

9. In combination with a printing die; protector means adapted to project beyond the impression surface of the die and prevent taking a simultaneous impression from the entire printing surface of the die while permitting taking a progressive impression from such surface, and means for operating the protector.

10. In combination with an orbitally moving printing die; protector means adapted to project beyond the impression surface of the die adjacent the end thereof to prevent taking a simultaneous impression from the entire printing surface of the die while permitting taking a progressive impression from such surface, and means for operating the protector.

11. In combination with a printing die; spaced protector means adapted to project alternately beyond the printing surface of the die, to prevent taking a simultaneous impression from the entire printing surface of the die while permitting taking a progressive impression from such surface, and means for operating the protector.
12. In combination with a rotatable printing die; spaced protector devices adjacent opposite ends of the die, adapted to alternately project beyond the printing surface of the die and permit taking a progressive impression from the surface of the die but prevent the simultaneous taking of an impression from all parts of such surface, and means for operating the protector.
13. In combination with a printing die; spaced protector devices adapted to be alternately projected beyond the printing surface of the die to permit taking a progressive impression from the surface of the die but prevent the simultaneous taking of an impression from all parts of such surface, and means for alternately retracting and projecting such devices.
14. In combination with an orbitally moving printing die; a pivoted protector adapted to project beyond the impression surface of the die to prevent taking an impression simultaneously from the entire printing surface of the die; and means for operating said protector.
15. In combination with a printing die; a rocking protector having spaced means adapted to project alternately beyond the printing surface of the die to prevent taking an impression simultaneously from all parts of the printing surface of the die; and means for operating said protector.
